UNITED STATES PATENT OFFICE.

HENRY FORD, OF DEARBORN, MICHIGAN.

DESIGN FOR A TRACTOR RADIATOR AND TANK ASSEMBLY.

52,734.

Specification for Design.

Patented Dec. 10, 1918.

Application filed September 27, 1918. Serial No. 255,985. Term of patent 14 years.

To all whom it may concern:

Be it known that I, HENRY FORD, a citizen of the United States, residing at Dearborn, in the county of Wayne and State of Michigan, have invented a new, original, and ornamental Design for a Tractor Radiator and Tank Assembly, of which the following is a specification, reference being had to the accompanying drawing, forming part thereof.

Figure 1 is a plan view of a tractor ra-

diator and tank assembly, showing my new design, and

Fig. 2 is a side elevation thereof.

I claim:

The ornamental design for a tractor radiator and tank assembly, as shown.

HENRY FORD.
